INVENTOR.

BY *John Zwalley*

UNITED STATES PATENT OFFICE

JOHN ZWALLEY, OF SAN ANTONIO, TEXAS

BACK PROTECTOR

Application filed October 31, 1927. Serial No. 230,159.

This invention relates to devices for protecting the backs of human beings at work, and has for its object to provide a means of relief from undue strain and fatigue.

Referring to the accompanying drawings, Fig. I represents a rear view of my back protector; Fig. II represents a front view thereof; and Fig. III represents a means of attaching shoulder straps to a belt that is to go 10 around a breast.

Referring further to the drawings, Fig. I represents a rear view of my back protector, the numeral 1 representing a pad of leather, canvas, or other suitable material. Within 15 the lower longitudinal portion of the said pad 1 is a rod 2 of metal or other suitable substance; to the lower longitudinal portion of the pad 1 is attached a cloth 3, which cloth is attached also to another smaller pad 4 which 20 consists of leather, canvas, or other suitable material, and a small plate 5 of metal or other suitable substance to add rigidity to the pad 4. From the lower longitudinal portion of this pad 4 cloth 3 extends to and is connected with 25 a third pad 6 which consists of leather, canvas, or other suitable material. Within the upper longitudinal portion of this pad 6 there is a rod 7 of metal or other suitable substance.

In the lower longitudinal portion of pad 1; 30 in rod 2; in the upper and the lower longitudinal portions of pad 4 and plate 5, and in the upper longitudinal portion of pad 6; and in rod 7 are holes into which the terminations of metal springs 8—9—10—11—12—13—14—35 15 are fastened. To pad 1 is attached a belt in two parts 16—17 and to part 16 and to the pad 1 are attached two shoulder straps 18—18, each strap terminating in a buckle and hook attachment 19—19 which may be connected 40 where desired in the row of eyelets 20 along the upper longitudinal portion of the belt part 16. Part 16 engages two connecting straps 21—21, at the lower termination of each of which straps is a buckle attachment 45 22—22. The upper terminations of the two straps 21—21 are formed into loops through which the belt part 16 is to pass. By means of the buckle attachments 22—22 at the lower terminations of the straps 21—21 these straps 50 are connected to a belt 23 that is to go around

the waist of a wearer of my back protector. This belt 23 is attached to the lower longitudinal portion of pad 6 by means of buckle attachments 24—24 that pass through slits 25—25 in pad 6.

Fig. II represents a front view of my back protector in which the numerals 3—3 represent the cloth referred to in my description of Fig. I. Numeral 26 represents a lining of felt on pad 1; numeral 27 represents a lining of felt on pad 4, and numeral 28 represents a lining of felt on pad 6, these linings of felt 60 26—27—28 being intended to rest against the back of a wearer of my back protector.

Fig. III represents a buckle and hook attachment in which the numeral 19 represents the hook by means of which the shoulder straps 18—18 may be connected with the belt part 16. It will be observed, when the terminations of the hook 19 are placed in eyelets along the upper longitudinal portion of the belt part 16, that each of the connecting straps 21 hereinbefore referred to appears between the two terminations of the hook 19, 70 and, in this manner, that the connecting 75 straps are held in place.

I claim:

In a back protector, a combination of reinforced back pads, an upper one, an intermediate one, and a lower one, disposed horizontally across the back of a wearer, the said back pads being connected to one another by cloth and by spring members, the upper back pad and the lower back pad being connected to each other by spring members of greater length, and a means for securing the upper part of the back protector over the shoulders and around the breast of a wearer and a means for securing the lower part of the back protector around the waist of a 80 85 90 wearer.

In testimony whereof, I affix my signature.
JOHN ZWALLEY.
